JOHN B. EHRLICH, OF INDIANAPOLIS, INDIANA.

COMBINATION STOVE AND GAS-RANGE.

1,172,235.

Specification of Letters Patent. Patented Feb. 15, 1916.

Application filed April 4, 1914. Serial No. 829,487.

To all whom it may concern:

Be it known that I, JOHN B. EHRLICH, a citizen of the United States, residing at Indianapolis, in the county of Marion and 5 State of Indiana, have invented a new and useful Combination Stove and Gas-Range, of which the following is a specification.

It is the object of my invention to provide a stove, and particularly a cooking 10 range, which can be used for either solid or fluid fuel, or for both such fuels at once, and can easily be converted from a condition for using one of such fuels to a condition for using the other or both, and vice 15 versa.

The accompanying drawings illustrate my invention in a range for the use of coal and gas, though my invention is not limited to the use of these particular fuels or in all 20 of its aspects to this particular kind of stove.

In these drawings, Figure 1 is a perspective view of a complete range embodying my invention; Fig. 2 is a somewhat similar 25 view showing the doors open and some of the parts removed; Fig. 3 is a vertical section through the lower part of the range, substantially on the line 3—3 of Fig. 4, also showing some features not shown in Figs. 30 1 and 2; Fig. 4 is a horizontal section on the line 4—4 of Fig. 3; Figs. 5 and 6 are vertical sections through the upper part of the range, one being perpendicular to the front of the range and one being parallel 35 thereto; Fig. 7 is a section on the line 7—7 of Fig. 5; Fig. 8 is a section on the line 8—8 of Fig. 6; Fig. 9 is a detail showing the mounting of the swinging brackets for the broiler; Fig. 10 is a view similar to 40 Fig. 9, but showing a solid broiler bracket; Figs. 11 and 12 are vertical sections somewhat similar to Figs. 5 and 6 respectively, but showing a modified construction; and Fig. 13 is a horizontal section substantially 45 on the line 13—13 of Fig. 11.

The stove "top" 10 on which ordinary cooking is done is supported at the desired height on legs 11, and is provided with a removable frame 12 which carries the ordinary stove lids 13. Above the stove top 10 are a rear wall 14 and side walls 15, surrounding which is a shelf 16 supporting the oven 17. The side walls 15 extend forward but part way along the stove top 10, and 55 sliding doors 18 are provided for coöperating with the walls 14 and 15 to inclose com-

pletely the space above the rear part of the stove top 10 while leaving the forward part open, as shown in Fig. 1, for lessening the escape of heat or odors into the room. Each 60 door has a single roller 19, near its center at the top, which roller travels in a grooved track 19'. The doors 18 also having flanges 18' at the top, which flanges carry the rollers 19 and also coöperate with the track 19' 65 to assist the rollers in supporting the doors.

The stove top is conveniently divided into three sections, as illustrated, beneath which is the heating chamber. Below the center section is located the fire pot 20, and below 70 that is an ash box 21, such ash box being in the form of a sliding drawer mounted within a casing 22 inclosing such fire pot and ash box. The front of the fire box is provided with a door 23, and the side of the 75 casing 22 with a sliding damper 24. The door 23 and the front of the drawer 21 may also be provided with draft-controlling devices if desired. Above the fire pot 20 is detachably mounted a gas burner, which 80 conveniently consists of perforated gas tubes 25 supported in holes 26 in the stove frame (see Figs. 2 and 3) and controlled by gas valves 27. Below the side sections of the 85 stove top are open spaces 28, which are the end sections of the heating chamber and are separated from the central section thereof above the fire pot and below the central section of the stove table by dampers 29 operable by sliding rods 30. The sliding 90 dampers 29 are connected by rods 31 to swinging dampers 32 connecting the spaces 28 with vertical flues 33 provided by the rear wall 14 and a U-shaped partition to the front of said rear wall. A swinging damper 32' operable by a rotatable rod 30' controls the direct connection of the space above the fire pot with the flue 33. The bottoms of the spaces 28 have upwardly extending, truncated cylindrical portions or tubes 28' 100 open at the bottom and provided at the top with removable sections or lids 35 (see the right hand side of Figs. 3 and 4), the removal of which sections or lids provides openings through which fluid fuel burners 105 36, here shown as gas burners, may be swung upward (as shown at the left of Fig. 3), such burners normally being lowered (as shown at the right of Fig. 3). To permit this swinging of the burners 36, such burners are attached to members 37 each having 110 a straight notch 38 and an angled notch 39

which respectively coöperate with fixed pins 40 and 41 on the range frame, the members 37 also being provided with operating handles 42, whereby the burners may be swung 5 around the pivot pin 40 and slid either forward or backward to cause the burner to be held up by the pin 41 and the horizontal portion of the slot 39 or to be allowed to drop by reason of the vertical portion of 10 said slot. The accompanying swinging in the gas supply connection for these burners takes place in the mixers 37 so that no swinging joint is necessary. Removably mounted plates 36' may be hung well below 15 the end sections of the heating chamber, so that any soot or grease which may drop through the tubes 28' when the plates 35 are removed will be caught. Within the flue 33 are mounted hot blast supply conduits 45, formed by U-shaped members attached to the rear face of the part 34, which conduits 45 communicate with inlet openings 46 in the front of the part 34 and with horizontal conduits 47 extending forward 25 beneath the central section of the stove top and above the fire pot. The inlet openings 46 are controllable by hand valves 48 (one of which is shown removed in Fig. 2), and the conduits 47 are provided with lateral 30 openings 49 which discharge heated air sideways and downward on to the fire within the fire pot to assist combustion.

The flue 33 extends past the rear edge of the shelf 16 to a partition 50 above and 35 spaced from said shelf. This provides a horizontal space or flue 50', which near its sides is provided with forwardly-extending baffle partitions 51, and near its forward edge may be provided with baffle tubes 52, which also 40 serve another function to be pointed out later. These baffle plates and tubes compel products of combustion passing up through the flue 33 to pass forward through the flue 50' and around the edges of the baffle partitions 51 into flues 53 extending upward at the sides of the oven 17 to a horizontal flue 54 above such oven. This horizontal flue communicating with the stove pipe or chimney 55 extending upward from it. The front 45 ends of the horizontal flues 50' and 54 may be provided with removable doors 56, for cleaning purposes. The baffle tubes 52 are open at the bottom, but at the top are provided with closing valves 57 carried by 50 screws 58, so that these tubes may be opened or closed as desired. At the bottoms of the tubes 52 are mounted fluid fuel burners 59, shown as gas burners, which are mounted to rotate about the axis of their fuel-supply 55 pipes 60 so that they will discharge either upwardly as shown in Fig. 5, or downwardly as shown in Fig. 6. The upward discharge is used for heating the oven 17, the valves 57 being open at this time, while 60 the downward discharge is for playing a

flame upon the upper surface of a broiler 61 which is removably and adjustably supported on swinging brackets 62. These brackets 62 at their upper ends have long pivot rods 63, mounted in supports 64 70 fastened to the range frame, and also have pins 65 which may coöperate with holes in the supports 64, as shown in Fig. 9. By shifting the brackets 62 endwise, the pins 65 are disengaged while the pins 63 remain in 75 engagement with their coöperating holes, thus permitting the bracket to be swung about the pins 63. This swinging is done automatically by springs 66, which tend not only to swing the bracket 62 to horizontal 80 position, as shown in dotted lines in Fig. 6, but also to move the brackets 62 endwise to bring the pins 65 into engagement with the coöperating holes in the bracket 64. Thus when the broiler is supported on the 85 brackets, as shown in Fig. 6, the brackets are held by the springs 66 in the position shown in Fig. 9; while upon the removal of the broiler 61 the brackets 62 are pulled forward slightly to disengage the pins 65 from 90 their coöperating holes, whereupon the springs 66 swing the brackets to their horizontal position. The partition 34 at the rear of and above the broiler 61 is provided with a sliding damper 68, so that the 95 products of combustion from the burners 59 when the latter are directed downwardly may pass out into the flue 33 and upward through the flues 50', 53, and 54, and the smoke pipe 55. The damper 68 also serves 100 as a check-draft when coal is used as fuel. Above the partition 50 and within the oven 17 is a horizontal partition 70, which provides between it and the partition 50 a space 71 closed at the front and sides but 105 open at the rear and at points above the valves 57. This causes the flames from the burners 59, when such burners are upwardly directed, to pass around the edges of the valves 57 and to be diverted back again into 110 an upward course, thus preventing such flames from coming forward against the oven door 72. The oven is provided with the usual oven shelves 73 adjustable to desired heights. At the top of the oven there 115 is a horizontal space 74, provided by a partition 75 and the roof 76 of the oven, and this space 74 is open at the front end to the space within the oven, and at the rear end to a curved passageway 77 which communicates 120 with the horizontal flue 54. This space 74 is preferably laterally contracted at its center portion, so that better radiation from the flue 54 may be obtained when coal is used as a fuel. A suitably operated damper 125 78 may be provided for closing the communication between the space 74 and the passageway 77.

The various fluid fuel burners may be supplied with fuel from a suitable supply 130

pipe 79, which conveniently connects with all such burners.

When the range is used for coal, the burners 36 are swung down, the burners 25 are removed, the plates 35 are put in place, the rods 30 are pushed in to open the dampers 29 and 32 if the side sections of stove are to be used and pulled out if they are not to be used and a concentrated heat is desired on the center section, the damper rod 30' is turned to open the damper 32' if the dampers 29 and 32 are closed, and usually to close the damper 32' if the other two dampers mentioned are open, and the valves 57 and the damper 78 and usually also the damper 68 are closed. The draft for the coal fire in the fire pot 20 is controlled by the damper 24, the air valves 46, the damper 68, and even the doors 56 if necessary. Also the ash drawer 21 may be slid partly out to provide greater draft, if desired. The products of the combustion of the fire pass through the opening provided by the damper 32' or through the openings provided by the dampers 29 and 32, into the flue 33, ascending therethrough to the horizontal flue 50' and circulating around the baffle partitions 51 and baffle tubes 52, passing thence into the side flues 53 on into the horizontal flue 54 above the oven escaping through the smoke pipe 55. This heats the stove top directly, and the oven by the passage through the flues mentioned of the hot products of combustion, such flues practically surrounding the oven. None of the products of combustion get into the oven itself. Baffles 28" may be provided for compelling these products of combustion to pass through all parts of the end sections of the combustion chamber.

When fluid fuel, such as gas, is used, the plates 35 are removed, the burners 36 are swung up into operative position, the burners 25 are put in place, the dampers 29, 32, 45 and 32' are usually but not necessarily closed, and cooking is done on the stove table in the ordinary manner of gas stoves. If the oven is to be used, the burners 59 are directed upwardly and the valves 57 are open, as shown in Fig. 5, the damper 78 also being opened to allow the escape of the gas fume from the oven. If desired, the gas heating of the oven may be used in conjunction with the coal heating thereof already described. When broiling is to be done the gas burners 59 are directed downwardly and the broiler 61 is hung on the brackets 62 in proper position, the gas fumes escaping through the now open damper 68, and the valves 57 preferably being closed. If desired the brackets 62 may be made solid, as shown in Fig. 10, so that by leaving the broiler in place and closing the doors 18 the fumes from odoriferous cooking may be prevented from escaping into the room

or entering the oven, even if the valves 57 are open, such fumes instead being carried off through the hot blast conduits.

Instead of the construction of gas burner 59 and associated parts shown in Figs. 5, 6, 7, the construction shown in Figs. 11, 12, and 13 may be used. The flues 33, 50', and 53, and the baffle partitions 51, are substantially the same as in the construction already described. However, in place of the circular baffle tubes 52, I use a single rectangular inclosing partition 80 within the lower end of which are mounted tubular burners 81 instead of the circular burners 59 of the construction first described. The openings in the tubular burners 81 may be directed either upwardly or downwardly by turning these tubes about their axes. The upper end of the opening through the partition 80 is surmounted by a valve 82 supported on vertical sliding bars 83 working in slideways 84 carried by the partition 80. By sliding the rods 83 upward or downward, as by rotatable rods 85 connected to the bars 83 by rack and pinion connections, the valve 82 may be made to open or close the upper end of the opening formed by the partition 80, the valve 82 being extended at the sides and rear so that it also acts as a baffle plate to direct the flames from the burners 81 toward the sides of the oven when the oven is being heated by gas or other fluid fuel and the valve 82 is thus correspondingly raised.

For cleaning the stove, the doors 56 are removed and the collected soot is scraped from the flue 54 into the side flues 53, the walls of these side flues are scraped, the soot is scraped from the bottoms of the side flues around the baffle partitions 51 and then from the flue 50' into the flue 33, the bottom of which is provided with a hopper 90 having a removable door 91 discharging into the ash drawer. The shelf 50 at the upper end of the flue 33 may be provided with a removable door 92, through which a scraper may be inserted to scrape the side walls of such flue.

I claim as my invention:

1. A stove which is convertible for solid and fluid fuel, comprising a heating chamber divided into compartments, a fire pot mounted in one of said compartments, a damper between such fire pot and the adjacent compartment, the bottom of said last-named compartment being provided with removable plates, and pivotally mounted fluid fuel burners which may be swung up through the bottoms of such last-named compartment when said removable plates are removed, said fluid fuel burners being carried by members which are each provided with a horizontal slot and a slot having vertical and horizontal portions, and fixed pins mounted in said slots, whereby

- the burners may be swung upward or downward and by horizontal motion may be locked in upper position.
2. A stove which is convertible for solid and fluid fuel, comprising a heating chamber divided into compartments, a fire pot mounted in one of said compartments, a damper between such fire pot and the adjacent compartment, the bottom of said last-named compartment being provided with removable plates, pivotally mounted fluid fuel burners which may be swung up through the bottoms of such last-named compartment when said removable plates are removed, and a hand lever having a slot and pin connection with the burners for pivotally moving said burners.
3. A stove which is convertible for solid and fluid fuel, comprising a heating chamber having a plurality of compartments, a fire pot in one of said compartments, a sliding damper for closing or opening the draft passage from that compartment to the adjacent compartment, a flue, and a swinging damper having a rod connection with the first damper and operable therewith to open or close the connection between said last-named compartment and said flue, and a damper controlling a direct connection between said first-named compartment and said flue, and a fluid fuel burner removably associated with said second compartment.
4. A stove which is convertible for solid and fluid fuel, comprising a heating chamber having a plurality of compartments, a fire pot in one of said compartments, a sliding damper for closing or opening the draft passage from that compartment to the adjacent compartment, a flue, and a swinging damper operable with the sliding damper to open or close the connection between said last-named compartment and said flue, and a fluid fuel burner removably associated with said second compartment.
5. A stove which is convertible for solid and fluid fuel, comprising an oven, a fire pot, flues for conducting the products of combustion from such fire pot under and around said oven, a burner for fluid fuel located beneath said oven, the floor of said oven being provided with an opening above said fluid fuel burner for admitting flames therefrom into the oven, and a combined valve and baffle plate for controlling said opening, said burner being mounted so that it can be reversed to direct the flames either upward or downward, and a broiler hung below said oven in position to be heated by the flames from said burner when such flames are directed downwardly.
6. A stove which is convertible for solid and fluid fuel, comprising an oven, a fire pot, flues for conducting the products of combustion from such fire pot under and
- around said oven, a burner for fluid fuel located beneath said oven, the floor of said oven being provided with an opening above said fluid fuel burner for admitting flames therefrom into the oven, and a combined valve and baffle plate for controlling said opening, said valve and baffle plate being movable above and either toward or from the upper end of said opening to close or open it, said burner being mounted so that it can be reversed to direct the flames either upward or downward, and a broiler hung below said oven in position to be heated by the flames from said burner when such flames are directed downwardly.
7. In a stove, the combination of an oven, the floor of said oven being provided with an opening, a valve for closing said opening, a fluid fuel burner located below said valve and reversible to direct flames either upwardly through said opening into the oven or downwardly, and a broiler pivotally hung below said oven in the path of said burner when said flames are directed downwardly.
8. In a stove, the combination of a fluid fuel burner, the flames of which can be directed downwardly, a broiler, and swinging brackets for supporting said broiler below said burner, said brackets being pivotally mounted on a horizontal axis and slidably endwise, springs tending to move said brackets upwardly around their pivots and endwise along their pivots, and means operated by the spring-produced movement of said brackets along their pivots for holding said brackets in position to support the broiler.
9. In a stove, the combination of a fluid fuel burner, the flames of which can be directed downwardly, a broiler, and swinging and slidable brackets for supporting said broiler below said burner.
10. In a stove, the combination of a fluid fuel burner, the flames of which can be directed downwardly, a broiler, and swinging and endwise slidable brackets for supporting said broiler below said burner, said brackets being pivotally mounted on a horizontal axis, springs tending to move said brackets upwardly around their pivots, and means for holding said brackets in position to support the broiler.
11. In a stove, a heating chamber having a bottom of which a part is removable to form an opening, in combination with a fluid fuel burner supported outside of said heating chamber and swingingly mounted so that it can be swung up into said heating chamber through said opening when such removable part is removed, and means including a slotted lever for holding the burner in the position in which it extends through such opening into the heating chamber.
12. In a stove, a heating chamber having

- a bottom of which a part is removable to form an opening, in combination with a fluid fuel burner supported outside of said heating chamber and swingingly mounted 5 so that it can be swung up into said heating chamber through said opening when such removable part is removed, said burner being also slidable and being provided with locking means operated by such 10 sliding for holding it in position in which it projects through such opening into such chamber or allowing it to drop back out of such opening.
13. In a stove, a heating chamber having 15 a partition that divides the chamber into upper and lower sections, the partition having an upstanding tubular portion, said tubular portion being provided with a bodily removable cover which when removed leaves an opening through the partition, in combination with a fluid fuel burner mounted so that it can be swung up through the opening thus provided into the upper section of the heating chamber.
14. In a stove, a heating chamber having 20 a bottom with a tubular portion projecting up from such bottom, such tubular portion being provided with a removable cover which when removed leaves an opening 25 through such bottom into such chamber, in combination with a fluid fuel burner mounted so that it can be swung up through the opening thus provided into the heating chamber, said burner being also slidable 30 and being provided with locking means operated by such sliding for holding it in position in which it projects through such opening into such chamber or allowing it 35 to drop back out of such opening.
15. In a stove, a stove top with a heating 40 chamber below it, a removable gas burner in said heating chamber, an oven above and spaced from the stove top, flues at the sides top, and bottom of the oven, a flue leading 45 from the heating chamber to the first-named flues, an ash box below the heating chamber, doors permitting access to the first-
- named flues, a door permitting access from the oven to the flue leading from the heating chamber, and a discharge door for connecting said last-named flue with the ash box. 50
16. A stove which is convertible for solid and fluid fuel, comprising an oven, a fire-pot, flues for conducting the products of combustion from said fire-pot under and around said oven, a burner located beneath the flue which is under the oven, a tube located above said burner and passing through the flue and the floor of the oven for admitting flames from the burner into the oven, a combined valve and baffle-plate for controlling the passage through said tube, said valve and baffle-plate being movable above and either toward or from the upper 60 end of said tube to open or close the same, and means including a rack and pinion for operating the combined valve and baffle-plate. 65
17. A stove which is convertible for solid and fluid fuel comprising an oven, a fire-pot, flues for conducting the products of combustion from such fire-pot under and around said oven, a burner for fluid fuel located beneath the flue which is under the 70 oven, a tube located above said burner and passing through the flue and the floor of the oven for admitting flames from the burner into the oven, a combined valve and baffle-plate for controlling the passage through 75 said tube, and means for operating the combined valve and baffle-plate including guide-ways, legs for the valve engaging the guide-ways and provided with racks, a shaft carrying pinions engaging the racks, and an exterior handle for the shaft. 80
- In witness whereof, I have hereunto set my hand at Indianapolis, Indiana, this twenty-eighth day of March, A. D. one thousand nine hundred and fourteen.
- JOHN B. EHRLICH.
